Primary Examiner — Cynthia Ramirez*Assistant Examiner* — Laura H Yu(74) *Attorney, Agent, or Firm* — Cantor Colburn LLP(57) **CLAIM**

The ornamental design for a door for drum washing machine, as shown and described.

DESCRIPTION

FIG. 1 is a perspective view of a door for drum washing machine, showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof;

FIG. 8 is a side perspective view thereof; and

FIG. 9 is a cross-section view taken along line 9-9 of FIG. 2; and,

FIG. 10 is another perspective view thereof in an environment of use.

The broken lines in the figures illustrating portions of the door for drum washing machine and environmental structure form no part of the claimed design.

1 Claim, 9 Drawing Sheets(56)
